CLAIM

I claim the ornamental design for a medical injector with cap, as shown and described.

DESCRIPTION

FIG. 1 is a left side elevation view of a medical injector with cap;

FIG. 2 is a right side elevation view thereof;

FIG. 3 is a top plan view thereof;

FIG. 4 is a bottom plan view thereof;

FIG. 5 is a front elevation view thereof; and,

FIG. 6 is a rear elevation view thereof.

The broken lines shown in the drawings are for the purpose of illustrating portions of the medical injector with cap and form no part of the claimed design.
